SELF-LOCKING KEY

Frederic Schaefer, Pittsburgh, Pa.

Application April 9, 1937, Serial No. 135,949

5 Claims. (Cl. 85—8.5)

This invention relates to self-locking keys, and more particularly to keys comprising a cotter-pin provided with a wedge for spreading the free ends of the pin after the pin is driven into position.

This self-locking key is similar to the one shown in my allowed patent application Serial No. 22,740 for Cotter-pin. The key there shown comprises a cotter-pin having legs connected at one end by a head provided with an opening in line with the legs. A spreading member is slidably disposed in this opening and between the legs and is adapted to spread apart the free ends of the legs when it is driven inwardly of the head. The spreading member is provided with a lateral projection that limits its outward movement relative to the pin, but there are no means for positively locking the spreading member in its legs-spreading position.

It is among the objects of this invention to provide a self-locking key of the type just referred to in which there are means for locking the spreading member in legs-spreading position. This object is preferably accomplished by providing the cotter-pin legs and the spreading member with detents which are brought into inter-engaging relation when the spreading member is driven into legs-spreading position.

The preferred embodiment of the invention is illustrated in the accompanying drawing in which Fig. 1 is an edge view of my self-locking key partly broken away; Fig. 2 is a side view thereof; Fig. 3 is an edge view of the key with the legs-spreading member driven part way into the cotter-pin; Fig. 4 is an edge view, partly broken away, showing the spreading member in operative position; Fig. 5 is a side view of the key locked in a supporting member; and Figs. 6, 7 and 8 are enlarged cross-sections of the key taken on the lines VI—VI, VII—VII and VIII—VIII, respectively, of Figs. 2, 3 and 5.

Referring to Figs. 1 and 2 of the drawing, there is shown a cotter-pin having resilient legs 1 integrally connected at one end by a head 2 in the form of a loop provided with an opening 3 in line with the legs. The legs are of general channel shape with their side flanges 4 extending toward each other and with their free ends tapering toward each other to form end walls 6 (Fig. 2). Preferably, the outer portions of the legs normally diverge toward their free ends so as to temporarily hold the pin in place when it is inserted upwardly through an opening.

To spread the free ends of the legs farther apart in order to positively lock the pin in the

member in which it is inserted, a nail-like spreading member or wedge 7 is slidably disposed in opening 3 in the head and in the grooves formed by the channel-like pin legs. When the wedge is in its inoperative position its head 8 is spaced from the cotter-pin head and its tapered end is disposed behind end walls 6 of legs 1. The diverging pin legs can thus be pinched together without interference from the wedge sufficiently to permit the key to be inserted in the desired opening. To retain the wedge in the pin at all times the portion of it within the pin is provided with detents 9 adapted to engage the inner surface of the head at the sides of opening 3 to limit outward movement of the wedge relative thereto.

It is a feature of this invention that the cotter-pin and wedge are so formed that the wedge is positively locked in its legs-spreading position so that it can not accidentally work backwardly and allow the legs to draw together whereby the key might fall or work out of the opening in which it is disposed. Accordingly, the wedge and pin are provided with detents which interengage when the wedge is driven into operative position, and which can be disengaged only by pounding on the tapered end of the wedge to drive it backwardly in the cotter-pin. Preferably, a detent 11 is formed on the inner surface of one flange 4 of each leg 1, the two detents 30 being on opposite sides of the wedge whereby they are diagonally opposite each other as shown in Figs. 1 and 6. The wedge is likewise provided with a pair of detents 12 formed on opposite sides of the wedge diagonally opposite to each other 35 in position to engage detents 11 on the pin. All of the detents in the wedge may be formed after the wedge and pin are assembled by upsetting the desired areas of the wedge with a tool operating on the wedge through the space formed 40 by looped head 2.

As shown in Figs. 6 and 7, the distance between each leg detent 11 and opposite flange 4 is great enough to permit the adjacent wedge detent 12 to pass the leg detent. However, as the leg detents are disposed on opposite sides of the wedge they normally engage the opposite sides of the wedge and maintain it centered in the channel-like legs, as shown in Fig. 6, so that the wedge detents can not pass the leg detents unless the latter and the adjoining faces of the wedge are separated. It is possible to effect this separation because the leg detents are formed on diagonally opposite flanges of the legs. Accordingly, as the wedge is driven inwardly to spread the pin legs 55

the wedge detents engage the leg detents and move or cant them, together with the legs, laterally in opposite directions as shown in Figs. 3 and 7. The canting which is thus permitted by the loose fit of the wedge in the legs separates the opposite faces of the wedge from detents 11 and permits the wedge detents to pass the leg detents.

As soon as these detents pass each other the legs spring back to their original positions as shown in Figs. 4 and 8. The wedge is then in its operative position in which the free ends of the legs are spread apart far enough to prevent the key from being withdrawn from opening 13 (Fig. 5) in which it is disposed. The only way that the wedge can be withdrawn from its legs-spreading position is by canting legs 4 in opposite directions, as previously explained, to permit the wedge detents to slide back across the leg detents. As it is necessary to apply considerable force to the wedge to cause it to thus cant the pin legs, it will be understood that the likelihood of the wedge accidentally working out of legs-spreading position is avoided.

It will be noted in Figs. 6, 7 and 8 that there must be sufficient clearance between the key and the wall of opening 13 to permit the pin legs to cant as shown in Fig. 7.

According to the provisions of the patent statutes, I have explained the principle and construction of my invention and have illustrated and described what I now consider to be its best embodiment. However, I desire to have it understood that, within the scope of the appended claims, the invention may be practiced otherwise than as specifically illustrated and described.

I claim:

1. A self-locking key comprising a cotter-pin having legs connected at one end by a head provided with an opening, and a spreading member slidably disposed in said opening and between said legs and provided with a detent for limiting withdrawal of the member from the pin, said member being adapted to spread apart the free ends of said legs when driven inwardly of said head, and said member and legs being provided with inter-engaging detents for retaining the member in its legs-spreading position.

2. A self-locking key comprising a cotter-pin having resilient legs connected at one end by a head provided with an opening, said legs being channel shape with their flanges extending to-

ward each other, and a wedge slidably disposed in said opening and in said channel legs, said wedge being adapted to spread apart the free ends of said legs when driven inwardly of said head, and said wedge and one of said flanges being provided with inter-engaging detents for retaining the wedge in its legs-spreading position. 5

3. A self-locking key comprising a cotter-pin having resilient legs connected at one end by a head provided with an opening, said legs being channel shape with their flanges extending toward each other, and a wedge slidably disposed in said opening and in said channel legs, said wedge being adapted to spread apart the free ends of said legs when driven inwardly of said head, and said wedge and only two diagonally opposite flanges of said legs being provided with inter-engaging detents for retaining the wedge in its legs-spreading position. 10

4. A self-locking key comprising a cotter-pin having resilient legs connected at one end by a head provided with an opening, said legs being channel shape with their flanges extending toward each other, and a wedge slidably disposed in said opening and in said channel legs, said wedge being adapted to spread apart the free ends of said legs when driven inwardly of said head, only two diagonally opposite flanges of said legs being provided with inwardly projecting detents, and said wedge being provided with diagonally opposite detents adapted to engage the sides of said leg detents to lock the wedge in its legs-spreading position. 20

5. A self-locking key comprising a cotter-pin having resilient legs connected at one end by a head provided with an opening, said legs being channel shape with their flanges extending toward each other, and said legs normally diverging away from each other in the direction of their free ends, and a wedge slidably disposed in said opening and in said channel legs and provided with a lateral projection for limiting withdrawal of the wedge from the pin, said wedge being adapted to further separate the free ends of said legs when driven inwardly of said head, and said wedge and only two diagonally opposite flanges of said legs being provided with inter-engaging detents for retaining the wedge in its legs-separating position. 30 40 45 50
